JOSEPH F. STOKES, OF PHILADELPHIA, PENNSYLVANIA.

Letters Patent No. 88,675, dated April 6, 1869.

IMPROVED CAR-STARTER.

The Schedule referred to in these Letters Patent and making part of the same.

To all whom it may concern:

Be it known that I, JOSEPH F. STOKES, of the city of Philadelphia, county of Philadelphia, and State of Pennsylvania, have invented a new and improved "Self-Propelling Railway-Car;" and I do hereby declare that the following is a full, clear, and exact description of the construction and operation of the same, reference being had to the accompanying drawings, and to the letters of reference marked thereon, in which—

Figure 1 is a side elevation of my improved self-propelling railway-car, with one of the car-wheels removed.

Figure 2 is a plan view of same.

Figure 3 is a sectional view of fig. 2, on the line A-B.

Figure 4 is a sectional view, enlarged, of one of the axles, with its springs and gearing.

The object of my invention is to construct the running-gear of a railway-car so that the same will be self-propelling.

The power employed for operating the car consists of a coiled spring, arranged on the axles, which revolves them, and communicates motion to the wheels, the mechanism and operation being more fully described hereinafter.

The framing of the car is constructed in the usual manner, and consists of side pieces s and s', end pieces e and e', and braces a and a'.

On the sides s and s', at proper distances apart, are placed sets of pedestals, p, p¹, p², and p³.

Placed and working in pedestals p, at the front of the frame, is an axle, A, on which are placed car-wheels of ordinary construction.

Secured on and in the centre of the axle A, is a pinion, P.

The axle A is enclosed, from near its ends, to the pinion P, by tubes T and T', the said tubes being made sufficiently large to allow the axle to turn freely in them.

On each side of the pinion P, and secured on the tubes T and T' by means of set-screws, are spur-wheels S and S'.

The outer ends of the tubes T and T' have secured to them coiled springs C and C', the said springs being also secured to the inner side of the barrels, or disks B and B', which are placed inside of the car-wheels, and enclose the springs.

Secured to the inner side of braces a and a', are iron straps I and I', each being made with an offset, in order to bring the lower ends, which encircle the tubes T and T', as near the spur-wheels S and S' as possible, thus serving as bearings for the tubes, and preventing friction on the axle.

Passing through and working in pedestals p¹, is a shaft, H, bearing on it a loose spur-wheel, S², which gears with the pinion P.

Tubes, or collars are shrunk on the shaft H, on each side of the spur-wheel S², on which are feathered two

shifting-pinions, N and N'. The said pinions gear with the spur-wheels S and S¹, and also connect with the spur-wheel S², by means of clutches formed on their hubs.

The pinions N and N' are thrown in and out of gear by means of levers L and L', the ends of which project a short distance beyond the front of the car, and are operated by means of a lever, R, or a crank, K.

The teeth on the spur-wheels S and S¹ are each provided with a pawl, l and l', which drops into them, and are thrown in and out of contact with the teeth by means of handles h and h'.

In building a full-size machine, the barrels B and B' should be fully enclosed, in order to prevent snow, ice, or dirt from passing in them and choking up the springs.

In describing my invention, it has been found only necessary to speak of the mechanism for operating the front wheels of the car, as an exact counterpart is used for operating the rear ones.

The gearing operating the rear wheels of the car should be arranged so that motion will be given to them in the same direction as the front wheels.

The spur-wheels and pinions at the rear of the car are thrown in and out of gear from the front of the car, by means of levers, or rods, not represented in the drawing.

Operation.

A crank is applied to either end of the shaft H, which are made square for the purpose.

The pinions N and N' have, in the mean time, been placed in gear with the spur-wheels S and S¹, by means of the lever R or crank K.

Power is now applied to the crank, which communicates motion to the spur-wheels S and S¹ by means of the pinions N and N'.

The spur-wheels being secured to the tubes T and T', to which the springs C and C' are also secured, they (the springs) are thus compressed, or wound up. The pawls l and l' hold the spur-wheels, and prevent the springs from running down.

The clutches on the pinions N and N' are now brought in contact with the spur-wheel S², and the pawls l and l' removed from the teeth of the wheels S and S'.

The springs C and C' will immediately commence to expand and turn the tubes T and T', carrying with them the spur-wheels S and S¹, which gear with and turn the pinions N and N' and shaft H. The spur-wheel S² being now in contact with the pinions N and N', by means of the clutches, consequently it will also receive motion, and communicate it to the pinion P and the axle A, to which the pinion is secured.

The car-wheels being secured to the axle, are thus turned, and the car propelled forward.

Having thus described my invention, its construction and operation,

What I claim, and desire to secure by Letters Patent of the United States, is—

1. The arrangement of the axle A, pinion P, tubes T and T', spur-wheels S and S¹, pawls l and l', coiled springs C and C', barrels, or disks B and B', straps I and I', on the front and rear of the car, and constructed to be operated by devices, substantially in the manner and for the purpose specified.

2. In combination with the above, the arrangement of the shaft H, spur-wheel S², shifting-pinions N and N', levers L and L', lever R, and crank K, substantially as and for the purpose set forth.

3. The within-described self-propelling railway-car, arranged and operating in the manner as herein shown and described.

In testimony whereof, I have hereunto signed my name, in the presence of two subscribing witnesses.

JOSEPH F. STOKES.
